UNITED STATES PATENT OFFICE.

ADOLPH MARTIN WIDERBERG, OF WORCESTER, MASSACHUSETTS.

CIRCUIT-INTERRUPTER.

1,290,449.

Specification of Letters Patent.

Patented Jan. 7, 1919.

Application filed November 17, 1917. Serial No. 202,576.

To all whom it may concern:

Be it known that I, ADOLPH MARTIN WIDERBERG, a citizen of the United States, residing at Worcester, in the county of Worcester and State of Massachusetts, have invented new and useful Improvements in Circuit-Interrupters, of which the following is a specification.

This invention relates to circuit interrupters, the object of the invention being to provide a device which will sound a warning or alarm when mounted upon and carried by a motor vehicle or automobile, when such vehicle is being operated or driven away by an unauthorized person, the improved device embodying means controlled by a rotating part of the driving mechanism of the vehicle such as the drive shaft, whereby an alarm may be sounded intermittently.

20 A further object of the invention is to provide a device of the character referred to, the construction of which is adapted to be easily and expeditiously applied to machines now in use.

25 With the above and other objects in view, the invention consists in the novel construction, combination and arrangement of parts, herein fully described, illustrated and claimed.

30 In the accompanying drawings:—

Figure 1 is a side elevation of a sufficient portion of a motor vehicle to illustrate the improved alarm in its applied relation thereto.

35 Fig. 2 is a view taken at right angles to Fig. 1, showing the drive shaft in cross section.

40 Fig. 3 is a vertical section through the alarm device taken in line with the drive shaft of a motor vehicle.

Fig. 4 is an elevation of the stationary member of the device.

Fig. 5 is a similar view of the rotary member thereof.

45 The improved interrupter for motor vehicles comprises a stationary or non-rotary member 1, and a rotary member 2 which is designed to be fastened to the drive shaft 3 of the motor vehicle so as to be turned thereby. The member 1 has a screw threaded connection with the lower shouldered end of a hanger 4 shown in the form of a rod which is mounted for vertical sliding movement in a tubular guide 4'. The upper end 50 of the guide 4' is shouldered and threaded and screwed into an attaching plate or sup-

port 5 secured by fastening means 6 to the bottom of the vehicle floor.

The main body of the member 1 comprises a body 7 of non-conducting material such as fiber, the same being surrounded by a reinforcing band 8 of metal. Secured to one side of the non-conducting body 7 is a race 9 containing a circular series of anti-friction rollers 10 which bear upon the drive 65 shaft 3, enabling said drive shaft to rotate freely within the member 1. The race 9 is split along the diametrical line 11 into semi-circular sections to enable the same to be applied to the drive shaft 3. Likewise the 70 body 7 is split along the diametrical line 12; also the band 8, the latter being formed with ears 13 through which is inserted suitable fastening or clamping means 14.

The rotating member 2 also comprises a 75 body 15 of fiber, a race 16 and a surrounding reinforcing band 17. All the parts 15, 16 and 17 are split along diametrical lines in the same manner as described in connection with the parts of Fig. 4 and have the same 80 purpose which is to admit of the application of the member 2 to the drive shaft 3. Lugs or ears 18 on the member 2 are clamped together by fastening means 19 and also tightly clamped in relation to and upon the 85 drive shaft 3. The member 1 is also provided with a race 16 and between the two races 16, there is interposed a circular series of anti-friction balls 20 which thus form a thrust bearing between the members 1 and 2. 90 Secured fixedly to the drive shaft 3 by means of set screws 21 or the equivalent thereof is a stop collar 22 which prevents the member 1 from moving endwise of the shaft 3, the member 1 being prevented from rotating by 95 the overhead means connecting the same to the vehicle floor as previously described.

All of the parts hereinabove described with the exception of the hanger 4 and the means for connecting the same with the vehicle floor are inclosed in the diametrically split casing 23 as shown in Figs. 1 and 2, said casing being formed in two similar sections having ears 24 through which are inserted bolts or other fasteners 25. Dust, dirt 105 and foreign matter are thus excluded from the working parts of the device.

From a source of electrical energy such as a battery 25', a circuit wire 26 extends to a hidden switch 27 which may be located at 110 any place to the machine which may be selected by the operator or owner. From the

switch 27 a wire 28 leads to a brush 29 which extends through an arm 30 of the non-rotary member 1. The rotary member 2 carries a metal plug 31 against which the brush 29 is adapted to wipe once in each rotation of the shaft 3 and the member 2. The plug 31 lies in contact with another plug 32 extending at a right angle to the plug 31 and projecting from the inner face of the rotary member so as to contact with the projecting portion of another metal plug 33 which extends through the member 1 and is threaded to receive a clamping nut 34 for a wire 35 which extends to an alarm 36 such as a bell or gong that may be located in a suitable cage under the car body if so desired. A wire 37 extends from the wire 35 to the alarm 36.

From the foregoing description taken in connection with the accompanying drawings it will now be understood that when the hidden switch 27 is closed, as the shaft 3 rotates, contact is made between the brush 29 and the metal plug 31 and between the plugs 32 and 33. This causes a current to pass through and sound the alarm 36 once in each revolution of the shaft 33. The

alarm 36 will have some distinguishing characteristic so as to advise persons in the vicinity of the machine that an unauthorized person is attempting to operate the same.

I claim:—

An electric alarm circuit interrupter for motor vehicles, comprising in combination, a diametrically split and substantially cylindrical casing; a non-rotary member, also diametrically split, adapting it to embrace a motor vehicle shaft, said stationary member carrying a laterally projecting electric contact, a diametrically split rotary member adapted to be fixedly mounted upon said shaft and having a laterally projecting electric contact adapted to coöperate with the first named contact to close a circuit in each revolution of said shaft, a brush carried by said non-rotary member, a contact for said brush carried by the rotary member and electrically connected to the first named contact of said rotary member, and a telescoping hanger supporting said casing and non-rotary member, said hanger adapted to be secured to a part of the vehicle.

In testimony whereof I, affix my signature.

ADOLPH MARTIN WIDERBERG.
